Primary Examiner — Justin M Jonaitis*Assistant Examiner* — Grace Doyle(74) *Attorney, Agent, or Firm* — Kilpatrick Townsend & Stockton LLP(57) **CLAIM**

The ornamental design for a chain for slide fastener as shown and described.

DESCRIPTION

FIG. 1 is a perspective view of a chain for slide fastener showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings are for the purpose of illustrating portions of the chain for slide fastener that form no part of the claimed design.

1 Claim, 5 Drawing Sheets(56)
